UNITED STATES PATENT OFFICE.

HUGH WILLIAMSON KELLY, OF WOODBRIDGE, NEW JERSEY.

TRACK TORPEDO AND METHOD FOR PRODUCING THE SAME.

Application filed August 3, 1928. Serial No. 297,156.

This invention relates particularly to track torpedoes of the type disclosed in my Patents Nos. 1,249,113, dated Dec. 4th, 1917, and 1,567,151, dated Dec. 29th, 1925. It is more particularly concerned with a new and improved method of producing the charge-carrying and rail-engaging portion of the torpedo, which in this instance are both formed of rubber.

10 An object of my invention is to produce a rubber torpedo carrier by a new and useful method.

Another object is to produce a rubber torpedo body without the necessity of using 15 tubing machines, molds, etc., or without employing mechanical aid other than suitable forms.

Still another object is to produce a rubber torpedo body by the method of wrapping the 20 rubber direct from the calendar or mill about suitable forms, and vulcanizing it while in position on the forms.

Other objects will hereinafter appear.

Referring to the specific exemplification 25 depicted in the drawings:

Fig. 1 is a perspective view showing the rubber as it comes from the calendar or mill, properly shaped about suitable forms;

Fig. 2 is a top plan of a completed tor- 30pedo;

Fig. 3 is a vertical section taken on the line 3—3 of Fig. 2;

Fig. 4 is a section at right angles to Fig. 3, taken on the line 4—4 thereof;

Fig. 5 is an end elevation of the completed 35 torpedo; and

Fig. 6 depicts a section through a rail, with a torpedo, shown in side elevation, in position thereon.

40 A sheet of rubber or other suitable material 1 is taken from the calendar or mill, as the case may be, and is shaped around forms 2, 2 as shown in Fig. 1. To properly locate and hold the ends 3, 3 of the sheet 1 in position, a form 4, slideable between the forms 2, 2, may be employed, though this can be omitted if desired.

45 Superposed upon the sheet 1, while in position on the forms 2, 2 and 4, is an additional form 5, over which is extended another sheet 50 of rubber or similar material 6, having ends 7, 7 extending beyond the form 5 and overlying the sheet 1, or this sheet 6 may be extended over the whole of 2, 2, making the 55 carrier thicker and stronger, if desired.

With the forms and sheets arranged in the

manner described, the material is suitably vulcanized. And the rubber may be reinforced with sheeting or duck 1^a to give it additional efficiency.

60 However, the steps of applying sheet 6 may be omitted if desired, and provisions made for accommodating the explosive charge in another manner.

The forms are then removed and the rubber blank cut into convenient sections, to form torpedo bodies.

As better shown in Fig. 3, an explosive charge 8 is inserted between the sheets 1 and 6 of each individual torpedo section, and the free ends 9, 9 of the sheet 6 are cemented or otherwise sealed to sheet 1, to make a closed or water-tight cover for the charge 8.

70 However, if desired, the charge 8 may be contained in a water-tight container, in which instance it would be unnecessary to seal the ends 9, 9.

75 Figs. 2 and 5 show, respectively, a top plan and a side elevation of the completed torpedo.

80 In Fig. 6 the torpedo shown in Fig. 3 is illustrated in operative position on a rail head 11, and it is readily seen how the intermediate portions 10 of the sheet 1 in Fig. 3 assume the positions depicted in Fig. 6.

85 It will also be clearly apparent that an enormous saving in time and expense results from my invention, and that the necessity of dies, extruding tubing, or the like, is entirely avoided.

90 I claim:

95 1. In the process of preparing a torpedo body, the steps of shaping a rubber sheet on forms around which the ends of the sheet are shaped to form leg portions and vulcanizing.

100 2. In the process of preparing a torpedo body the steps of shaping a rubber sheet on forms around which the ends of the sheet are shaped to form rail-engaging leg portions, inserting another form between the first-mentioned forms, to rigidly hold the ends of the sheet in place, and vulcanizing.

105 3. In the process of preparing a torpedo body, the steps of shaping a rubber sheet on forms around which the ends of the sheet are shaped to form leg portions, placing another form on top of the sheet, and another sheet over the last-mentioned form, so that its edges overlie the form and rest on the first-mentioned sheet, and vulcanizing.

110 4. In the process of preparing a torpedo

body, the steps of shaping a rubber sheet on forms around which the ends of the sheet are shaped to form leg portions, inserting another form between the first-mentioned forms, to firmly hold the ends of the sheet in place, placing another form on top of the sheet, positioning another rubber sheet over the last-mentioned form so that its ends overlie the form and rest on the first-mentioned sheet, and vulcanizing.

5. In the process of preparing a torpedo body, the steps of shaping a rubber sheet on forms around which the ends of the sheet are shaped to form leg portions, vulcanizing, and severing the sheet into sections suitable for torpedo blanks.

6. In the process of preparing a torpedo body, the steps of shaping a rubber sheet on forms around which the ends of the sheet are shaped to form leg portions, inserting another form between the first-mentioned forms to securely hold the ends of the sheet in place, vulcanizing, and severing the sheet into sections suitable for torpedo blanks.

7. In the process of preparing a torpedo body, the steps of shaping a rubber sheet on forms around which the ends of the sheet are shaped to form leg portions, placing another form on top of the sheet, positioning another sheet over the last-mentioned form with its ends overlying the form and resting on the first-mentioned sheet, vulcanizing, and severing the resulting vulcanized blank into sections suitable for torpedo blanks.

8. In the process of preparing a torpedo body, the steps of shaping a rubber sheet on forms around which the ends of the sheet are shaped to form leg portions, inserting another form between the first-mentioned forms, to firmly hold the ends of the sheet in place, placing another form on top of the sheet, positioning another rubber sheet over the last-mentioned form so that its ends overlie the form and rest on the first-mentioned sheet, vulcanizing, and severing the resulting vulcanized blank into sections suitable for torpedo blanks.

9. The process of forming a torpedo for railway tracks and the like, comprising the steps of shaping a rubber sheet on forms around which the ends of the sheet are shaped to form leg portions, vulcanizing the sheet while on the form, cutting the vulcanized sheet into sections suitable for torpedo blanks, and placing and securing a charge on top of each blank.

10. The process of forming a torpedo for railway tracks and the like, comprising the steps of shaping a rubber sheet on forms around which the ends of the sheet are shaped to form leg portions, inserting another form between the first-mentioned forms, to rigidly hold the ends of the sheet in place, vulcanizing the rubber while on the forms, severing the vulcanized sheet into sections suitable for

torpedo blanks, placing and securing a strip thereover to hold a charge in position, and securing a charge between the top of the torpedo blank and the said strip.

11. In the process of preparing a torpedo body, the steps of shaping a rubber sheet on forms around which the ends of the sheet are shaped to form leg portions, placing another form on top of the sheet, positioning another sheet over the last-mentioned form, with its ends overlying the form and resting on the first-mentioned sheet, vulcanizing, severing the vulcanizing sheet into sections suitable for torpedo blanks, and inserting a charge into the cavity formed between the first sheet 75 and the second sheet.

12. In the process of preparing a torpedo body, the steps of shaping a rubber sheet on forms around which the ends of the sheet are shaped to form leg portions, inserting another form between the first-mentioned forms to firmly hold the ends of the sheet in place, placing another form on top of the sheet, positioning another rubber sheet over the last-mentioned form, so that its ends overlie the form and rest on the first-mentioned sheet, vulcanizing, severing the resulting vulcanized sheet into sections suitable for torpedo blanks, and inserting a charge in the cavity formed between the first and second sheets. 90

13. The process of preparing a torpedo body, comprising the steps of shaping a rubber sheet on forms around which the ends of the sheet are shaped to form leg portions, placing another form on top of the sheet, positioning another sheet over the last-mentioned form, with its ends overlying the form and resting on the first-mentioned sheet, vulcanizing the rubber while in position on the forms, severing the vulcanized sheet into sections suitable for torpedo blanks, inserting a charge into the cavity formed between the first sheet and the second sheet, and securing the ends of the second sheet to the first sheet, to enclose the charge. 100

14. The process of preparing a torpedo body, comprising the steps of shaping a rubber sheet on forms around which the ends of the sheet are shaped to form leg portions, inserting another form between the first-mentioned forms to firmly hold the ends of the sheet in place, placing another form on top of the sheet, positioning another rubber sheet over the last-mentioned form so that its ends overlie the form and rest on the first-mentioned sheet, vulcanizing the rubber while positioned on the forms, severing the vulcanized sheet into sections suitable for torpedo blanks, inserting a charge in the cavity formed between the first and second sheets, and cementing the edges of the second sheet to the first sheet. 115

15. A torpedo blank comprising a rubber face having down-turned legs at the longitudinal extremities thereof, and inturned flanges 125

adjacent the extremities of the legs; and a rubber sheet on the top of the face, extending longitudinally thereof, and secured adjacent its ends to the face, said face and said sheet defining a cavity to receive a charge.

16. A torpedo blank comprising a rubber surface having down-turned legs at the longitudinal extremities thereof, and inturned flanges

adjacent the extremities of the legs; webbing on the underside of the face, legs, and flanges, to reinforce the same; and a rubber sheet on the top of the face, extending longitudinally thereof, and secured adjacent its ends to the face, said face and said sheet defining a cavity to receive a charge.

HUGH W. KELLY.
